UNITED STATES PATENT OFFICE

ARTHUR G. MILLER, OF ATKINSON, NEBRASKA

PROGRAM CALENDAR

Application filed February 18, 1931. Serial No. 516,793.

The present invention relates to signs and display devices, and more particularly to a device adapted to be placed on exhibition to announce theatricals, motion picture plays and the like, information of public interest, and to associate with this general information certain advertising matter so that the advertising matter will be forcibly brought to the attention of the general public.

10 Another object of the present invention is to provide a sign board or the like with a centrally disposed and detachable pad of sheets bearing certain consecutively and pre-arranged programmes and to provide the board or sign with marginal panel portions for the reception of advertising display matter and also legends or the like indicative of the theatre or other place of public meeting associated with the information contained 20 on the sheets of the pad.

With the foregoing and other objects in view, the invention will be more fully described hereinafter, and will be more particularly pointed out in the claim appended 25 hereto.

In the drawing, wherein like symbols refer to like or corresponding parts throughout the several views:

Figure 1 is a face view of a sign or display device constructed according to the present invention.

Figure 2 is an edge elevation of the same.

Figure 3 is a detail plan view of the body board of the sign with parts removed therefrom.

Figure 4 is a detail rear elevation of the detachable pad for mounting upon the face of the sign board of Figure 3, and

Figure 5 is an edge view of the pad shown in Figure 4.

Referring to the drawing, 10 designates a base board which may be of cardboard, wood, metal or any suitable material or composition of materials, and which preferably is of flat rectangular shape adapted to be positioned substantially vertically with one flat side thereof exposed for supporting the informative and advertising matter.

The base board 10 may be provided at its upper edge portion and between its lateral

edges with an opening 11 adapted to receive a hooked nail or other suspension device when it is desired to hang the sign against a wall, post or other support at a suitable distance above the ground.

The base board 10 is also provided, at its lower end portion, with an easel 12 which comprises a substantially triangularly shaped flap having an attaching strap 13 secured against the rear side of the body board 10 in vertical position so that, as shown in Figure 2, when the easel 12 is swung outwardly at substantially right angles to the board 10 the easel provides a suitable support to maintain the base board 10 in a substantially upright position.

The base board 10 is provided in its outer surface, as shown in Figure 3, with a centrally disposed panel 14 which may be defined by depressing the outer surface of the base board 10, or by marginal edge lines 15 which may be printed, painted or otherwise suitably disposed upon the outer surface of the board to define the central panel.

Above the central panel 14 the base board 10 is provided with a narrow horizontal slot 16 which is centered or aligned with the upper end of the panel 14, as clearly shown in Figure 3, and which is of such size and length as to freely receive therethrough the flap or tongue 17 carried upon the upper rear side portion of a pad 18 of display sheets. The display sheets 18 are substantially of the size of the panel 14 and may be proportioned according to the size of the panel to fill or cover, or substantially fill or cover, the panel 14 as desired.

The pad 18 comprises a plurality of independent sheets which are secured together detachably at their upper ends so that the sheets of the pad may be torn off one at a time for exposing subjacent sheets throughout the life of the pad. Each sheet of the pad is adapted to be different from the preceding one and may be of the construction and type shown in Figure 1.

In Figure 1, the first sheet of the pad 18 is provided at its upper portion with a day and date space 19 which is set apart to contain, printed therein, the day or days and the

date or dates of the week and month upon which a motion picture is to be exhibited, and the lower portion of the sheet is arranged to display the name of the exhibition with data concerning the same and the reproduction or picture of a leading character or incident in the production.

The present description and illustration are in reference to a sign or exhibitor adapted for use by motion picture houses and it is understood that the subject matter which is placed on the display device or sign may of course be changed to suit conditions of display and place of public meeting.

15 As shown in Figure 3, the base board 10 is provided across its upper intermediate portion, and above the slot 16, with a top panel 20 adapted to contain the name of the theatre and its location, and the front 20 face of the base board 10 is also provided at opposite sides and across its bottom with advertising panels 21 arranged in suitable size and number to accommodate the marginal portion of the base board 10 and the 25 number of advertisements which are adapted to be displayed.

The central panel 14 thus provides an information panel in which the desired information as to time and substance of meetings, motion pictures and the like which are to take place is set forth and the panels 21 are so disposed about the information panel 14 that they will be exposed to view and will attract the public eye.

35 By use of this invention, the pad 18 may be made up of a number of sheets corresponding to the number of meetings, performances or the like which are pre-arranged, so that from period to period, such as from day to 40 day, a sheet may be torn from the pad so as to expose the succeeding sheet and thus show on the front of the sign or display device the subject matter desired for future dates.

It is apparent that the pad 18 may be quickly and easily positioned and removed with respect to the base board 10 by merely inserting or withdrawing the tongue 17 at the back of the pad through the slot 16. The tongue 17 is connected to the upper edge portion of the pad so that the tongue, being located wholly at the rear side of the base board 10, overcomes by its weight and leverage the suspension weight of the pad 18 at the front face of the base board. Thus, the 55 arrangement of the tongue 17 provides a quick and easy means for placing and removing the pads on the base board.

All of the panels in the front side of the base board 10 may be delineated by depressing the panels in the front face of the base board or by defining the panels with marginal lines or other configurations, such as at 15.

It is obvious that various changes and 60 modifications may be made in the details of

construction and design of the above specifically described embodiment of this invention without departing from the spirit thereof, such changes and modifications being restricted only by the scope of the following claim.

What is claimed is:

An advertising sign comprising a flat base board, an easel support for said board for holding the same in upright position, said board having an outer face divided into a central panel and a plurality of border panels surrounding the central panel, said base board also provided at the upper end of said central panel with a transverse slot extending throughout the width of the central panel, and a pad of sheets conforming in length and width substantially to that of the central panel removably fitting thereagainst, said pad of sheets having securing means at their upper ends for holding said sheets together in suspended relation, said securing means provided with a depending tongue of substantially the width of the pad of sheets extending downwardly at the rear side thereof and spaced from the rear-most sheet a distance sufficient to engage through said slot of the base board, said tongue adapted to engage against the rear side of the base board for securing the pad of sheets detachably in the said central panel of the base board.

In testimony whereof, I have affixed my signature.
